(57) CLAIM

The ornamental design for a decorative post cover as shown and described.

DESCRIPTION

FIG. 1 is a top, front, right perspective view of a decorative post cover, showing my new design;

FIG. 2 is a top, rear, left perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines shown in the drawings represent portions of the decorative post cover that form no part of the claimed design.

1 Claim, 5 Drawing Sheets(56)
